(57) **CLAIM**

The ornamental design for a lid for container, as shown and described.

DESCRIPTION

FIG. 1 is a perspective view of a lid for container in accordance with a first embodiment of the present design;

FIG. 2 is a front elevation view of the lid for container of FIG. 1, the rear elevation view being a mirror image thereof;

FIG. 3 is a right-side elevation view of the lid for container of FIG. 1, the left-side elevation view being a mirror image thereof;

FIG. 4 is a top plan view of the lid for container of FIG. 1;

FIG. 5 is a bottom plan view of the lid for container of FIG. 1;

FIG. 6 is a perspective view of a lid for container in accordance with a second embodiment of the present design;

FIG. 7 is a front elevation view of the lid for container of FIG. 6, the rear elevation view being a mirror image thereof;

FIG. 8 is a right-side elevation view of the lid for container of FIG. 6, the left-side elevation view being a mirror image thereof;

FIG. 9 is a top plan view of the lid for container of FIG. 6;

FIG. 10 is a bottom plan view of the lid for container of FIG. 6;

FIG. 11 is a perspective view of a lid for container in accordance with a third embodiment of the present design;

FIG. 12 is a front elevation view of the lid for container of FIG. 11, the rear elevation view being a mirror image thereof;

FIG. 13 is a right-side elevation view of the lid for container of FIG. 11, the left-side elevation view being a mirror image thereof;

FIG. 14 is a top plan view of the lid for container of FIG. 11; and,

FIG. 15 is a bottom plan view of the lid for container of FIG. 11.

The broken lines in some figures are for illustrative purposes only and form no part of the claimed design.
